FIRE EXTINGUISHER

Ralph W. Austin, Weymouth, Mass., assignor to Process Engineering Inc., Somerville, Mass., a corporation of Massachusetts

Application April 11, 1955, Serial No. 500,324

2 Claims. (Cl. 169—31)

This invention relates to a fire extinguisher.

In general the object of the invention is to provide a novel and highly efficient fire extinguisher of the type wherein an extinguishing medium is expelled from the extinguisher casing by gas pressure released from a pressurized sealed cartridge by puncturing the cartridge when the extinguisher is to be operated. The invention contemplates an extinguisher which is simple in construction, may be economically manufactured and recharged in a simple manner and in a minimum of time.

With this general object in view and such others as may hereinafter appear the invention consists in the fire extinguisher and in the various structures, arrangements and combinations of parts hereinafter described and particularly defined in the claims at the end of this specification.

In the drawings, the figure is a vertical elevation with portions in section illustrated in the preferred embodiment of the present invention.

The present invention contemplates an improved fire extinguisher of the type in which an extinguishing medium is expelled from the extinguisher casing by gas pressure released from a pressurized sealed cartridge. Provision is made for supporting the cartridge in a novel and improved manner and for insuring a free flow of the pressurized gas from within the cartridge to within the extinguisher casing.

Referring now to the drawing, 10 represents the extinguisher casing having a threaded neck portion 12. A cap 14 provided with threads 16 is screwed on the threads 18 in neck portion 12 to close and seal the same. Provision is made for supporting a sealed pressurized cartridge 36 containing, for example, a supply of carbon dioxide in the form of Dry Ice under pressure within the upper portion of the extinguisher casing. Piercing mechanism is supported within the cap 14 for piercing the pressurized cartridge 36 when it is desired to operate the extinguisher.

As illustrated in the drawing, the upper portion of the cap 14 is provided with upstanding portion 20 having an internally threaded portion as at 22 into which an externally threaded plug 24 is screwed to clamp a flange 25 of a resilient rubber plunger 30 against the interior of the portion 20 of the cap. The upper end of the plunger 30 is arranged to extend upwardly through a hole in upstanding portion 20 to project above the upper surface thereof, and above the usual handle on the extinguisher casing as shown. The rubber plunger 30 is provided with a longitudinally extended metal puncture pin 32 molded therein, the lower end of which is sharply pointed and extends a predetermined distance into the neck portion 12 of the extinguisher casing 10 when the cap 14 is screwed tightly upon said neck 12.

The cartridge 36 is preferably provided with a cylindrical body portion 38 open at one end 40 and is further provided with an integral flange portion 42 adjacent its open upper end. The upper portion of flange 42 is provided with an outwardly turned integral annular rim 43 arranged to be seated upon the rim of neck 12, as shown,

2

and in this manner container 36 is suspended within casing 10. Provision is made for attaining a tight seal between cap 14 and rim 43 comprising an annular washer of any suitable material, such as rubber or the like, superimposed upon said rim 43 and compressed thereagainst by the bottom surface of cap 12 when said cap is screwed tightly upon the neck of casing 10. In practice the cartridge is filled with a supply of Dry Ice and sealed by cap 46 welded to the upper open end thereof, as shown.

The top portion 52 of the cap 46 is preferably of relatively thin, puncturable material which may be easily perforated by puncture pin 32 when it is desired to operate the extinguisher.

In order to provide and maintain a free flow of gas from within the cartridge 36 to be metered into the extinguisher casing to pressurize the same a cup-shaped metering disk 50 is welded within the cap 46 with its open end adjacent the thin, puncturable top portion 52 of said cap 46. The metering disk 50 is provided in its bottom with a metering hole which is generally funnel-shaped in section having the wider end 54 of the metering opening centered within the cap 46, the narrow end 56 being spaced a short distance upwardly therefrom. The narrow portion 56 of said hole may be of any desired size and preferably will be of a size equivalent to the hole formed with a No. 77 drill and is centered directly beneath and in alignment with the pointed tip of puncture pin 32. In order to prevent impurities from clogging the narrow portion 56 of the meter hole a wire mesh screen 58 of a size sufficient to completely extend across and cover the interior of the cap is welded to the interior walls thereof immediately below metering disk 50 between it and the interior of cartridge 36.

One of the principal difficulties which is encountered in the operation of the fire extinguishers of this general type now on the market has been that impurities, which may be found in the gas generating chemicals themselves or may be small particles of carbon dioxide in its solid form, are deposited upon the surface of the filtering screen, thoroughly clogging the same. The prior art metering disk now found in various types of extinguishers on the market is usually a flat disk having the metering hole drilled in the center thereof, and a filtering screen of fine mesh is positioned adjacent said disk between it and the gas generating chemical container. In practice when the gas generating chemical container is punctured and gas released the pressure of the escaping gas forces the filtering screen against the disk, and any particles deposited on said screen partially or totally clog the hole, impairing or destroying the efficiency of the extinguisher. This is particularly true because of the small size of said metering hole.

In accordance with the present invention the tendency of the filtering screen to become clogged is substantially eliminated by the particular structure and arrangement of the present metering disk 50 and the location of the metering hole with relation to the fine wire mesh filtering screen 58. It will be observed that when the puncturable top 52 of the cap 46 is punctured by puncture pin 32 in the manner hereinafter to be described, the escaping gas from within the body of the cartridge 36 will cause filter screen 58 to move upwardly against the wider part of the funnel-shaped metering hole. In practice the area of said wide portion or entrance 54 of the metering hole is of sufficient size to permit a normal quantity of impurities to collect on the screen 58 and still be of sufficient diameter to permit the gas to pass freely therethrough to be metered through the metering aperture and into the interior of the extinguisher casing.

In order to allow the metered flow of gas flowing

through metering disk 50 to enter the body of the extinguisher casing to pressurize the same, flange 42 is provided with a plurality of spaced openings 60 communicating with the interior of casing 10.

In operation when it is necessary to operate the present extinguisher, the rubber plunger 30 is depressed either by hand pressure or may be easily operated by inverting the entire casing and striking the top of plunger 30 in contact with a solid surface. The weight of the casing of itself may be sufficient to depress the plunger 30, causing pin 32 to pierce the frangible top of the cap 46 and to thus release the pressure from within cartridge 36. When such pressure is released the plunger will, due to its resiliency, return pin 32 to its normal position. When Dry Ice is utilized as the gas generating medium the sudden release of pressure causes it to react to attain its normal gaseous state. Such gas will then flow through screen 58, metering disk 50 and into the area 61 beneath extinguisher casing cap 14 and flange 42 to thereafter flow through openings 60 in said flange into the body of casing 10, pressurizing the same in a very even, rapid manner.

In practice the body of the extinguisher casing may be filled with any known extinguishing fluid, such as water and the like, as illustrated in the drawing at 65. Provision is made for directing a stream of such fluid onto a fire when the extinguisher is put in operation and the body pressurized, as heretofore described, including an outlet 66 formed in the upper end of casing 10, as shown, provided with a suitable coupling 68 to which a hose 70 and nozzle 72 may be connected in any usual manner. In order to prevent sediment or other impurities from clogging the outlet 66, hose and nozzle 70, 72 and a filter screen 74 of any type found on the market are preferably secured to the casing wall covering said outlet 66, as shown.

From the foregoing description it will be apparent that the present fire extinguisher may be maintained in perfect operating condition for long periods of time by recharging and may be quickly and efficiently refilled and recharged in a simple, economical manner. A plurality of gas generating cartridges 36 may be kept on hand, and during a fire the extinguisher may be quickly recharged and used a number of times by quickly changing the containers and refilling the casing with water or other fluid.

Having thus described the invention, what is claimed is:

1. A fire extinguisher comprising an extinguisher casing having an opening in the upper end thereof and an externally threaded neck surrounding the opening, said casing containing a body of extinguishing medium and being provided with an outlet, a cap screwed upon the threaded neck closing the opening in the casing, a puncturable pressurized cartridge operatively supported within the casing a short distance below the cap, a resiliently mounted puncturing member operatively supported in the cap and adapted when depressed to puncture said pressurized cartridge, said cartridge comprising a body portion and a cup-shaped cap member welded to the body portion and having a cup-shaped screen welded to the interior of the cap and extending across the same, and a cup-shaped metering member also welded to the interior of the cap and provided with an upwardly tapering opening therein disposed between the screen and the puncturable top of the cartridge.
2. A fire extinguisher comprising an extinguisher casing open at one end, a cap for detachably closing said opening, manually operated puncturing means carried by the cap, an extinguisher medium within said casing, a container for a supply of pressurizing medium having means integral therewith for suspending said container within the body of the extinguisher casing including an annular flange having a plurality of openings therein, an annular rim adapted to be detachably supported upon the open end of the casing and secured in position by the casing cap, a frangible cup-shaped cap for sealing the container having a cup-shaped metering disk secured thereto and disposed therein and provided with a funnel-shaped metering hole, one end of said hole being wider than its opposed end, a filtering screen covering the wide end of said hole to prevent impurities from clogging said metering hole to permit the pressurizing medium to flow through the metering hole into the body of the casing, and to pressurize the same to expel the extinguisher medium from within the casing.
